(57) **CLAIM**

The ornamental design for a frozen confection, as shown and described.

DESCRIPTION

FIG. 1 is a perspective view of a frozen confection showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Broken lines show environmental structure and form no part of our claimed design.

The denser stippled shading and less dense stippled shading shown in FIGS. 1-7 represent a contrasting appearance.
